ELECTRIC MIXER BLADE OR SIMILAR ARTICLE

Earl F. Rutan, Pound Ridge, N. Y., assignor to Loral
Electronics Corp., Bronx, N. Y., a corporation of New
York

Application March 5, 1958, Serial No. 49,906

Term of patent 14 years

(Cl. D44—1)

*Fig. 4**Fig. 1**Fig. 2**Fig. 3*

Figure 1 is a view in perspective of an electric mixer blade or similar article showing my new design.

Figure 2 is a side elevational view thereof as seen from the plane 2—2 on Figure 1;

Figure 3 is a bottom plan view thereof; and

Figure 4 is a side elevational view as seen from the plane 4—4 on Figure 1.

I claim:

The ornamental design for an electric mixer blade or similar article, substantially as shown.
